SEDWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

SIGNALING MEANS.

1,330,106.

Specification of Letters Patent. Patented Feb. 10, 1920.

Application filed October 7, 1911, Serial No. 653,342. Renewed August 2, 1919. Serial No. 314,986.

To all whom it may concern:

Be it known that I, SEDGWICK N. WIGHT, a citizen of the United States, and resident of the city of Rochester, in the county 5 of Monroe and State of New York, have invented a new and useful Signaling Means, of which the following is a specification.

This invention relates to a track circuit controlled device.

10 The primary object of this invention is to produce the closing of a normally open circuit by the movement of a train onto a track circuit section from one direction, but to prevent the closing of the same open 15 circuit by a movement of a train from the other direction onto said section, and to further produce an opening of a normally closed break in the normally open circuit by the presence of a train upon an adjacent track circuit section.

20 In describing the invention in detail reference will be had to the accompanying drawings in which like characters of reference refer to like parts and in which, Figure 1, is a diagrammatic representation of the location of signals as ordinarily placed upon a single track automatic block signaled 25 railway; Fig. 2, is a diagrammatic representation of the preferred form of circuits for attaining the above stated primary object of my invention.

The signaling of single track railways is often accomplished by locating the signals as shown by Fig. 1. In this figure, numerals 1, 2, 3, 4, 5, 6, 7, 8, 9, 10, 11 and 12 designate block signals, which include the ordinary semaphore arm which is caused to move into the ordinary and well known positions by the operation of some form of 30 motor. The motor is controlled in its movements by the presence of a train upon the rails of the track either in advance of, or in the rear of the signal to which it is connected, or both. As ordinarily installed the signal 7 would exhibit the semaphore arm in the full clear or 90° position as shown by the figure, to a train approaching in the direction of the arrow x , if no train were present upon any portion of the track between 35 the insulating joint 13 and the insulating

joint 17. If a train were present upon any part of the track between insulating joints 13 and 16, the signal 7 would exhibit the semaphore arm in the 45° or caution position.

55

Signals 2, 6 and 11 are controlled similarly to signal 7.

Signals 3 and 4 are what are termed, "intermediate signals" and merely govern what are called "following moves", that is, they 60 keep trains which are moving in the same direction, properly spaced.

The signals 9 and 10 serve the same function as the signals 3 and 4, but govern 65 trains moving in the opposite direction.

65

The section of track included between the insulating joint 15 and the insulating joint 21, is what is termed a single track block, the entrance of trains thereto moving in opposite directions, is controlled by the signals 5 and 8. These signals are normal 70 danger signals, that is, in the absence of trains the semaphore arms of the signals are in the horizontal or danger position, but upon the approach of a train they move to 75 the full clear or 90° position if no train moving in the opposite direction is in the block and no train is in the block moving in the same direction as the approaching train. In the system of signaling invented by Wilmer W. Salmon and Frank L. Dodgson and 80 fully shown, described and claimed in application Serial No. 607,098, filed February 7th, 1910, a means is provided whereby the signal 5 or the signal 8 may assume the 45° 85 or caution position if a train is in the single track block when a following train approaches either of the signals.

The means for causing the signals 5 and 8 to assume the operated aspect is controlled 90 by the track circuit sections between insulating joints 14 and 15 for signal 8, and 21 and 22 for signal 5, the arrangement being such that the entrance of a train upon the section included between insulating 95 joints 14 and 15 moving in the direction of the arrow x , will cause the signal 8 to assume an operated aspect if no train is present upon any part of the trackway included between the insulating joints 15 and 22, 100

which is moving in a direction opposite to that of the approaching train, and the signal 5 will exhibit an operated aspect to a train approaching in the direction of the arrow y , when said train passes upon the section of track included between the insulating joints 21 and 22, if no train is present upon the trackway included between the insulating joint 21 and the insulating joint 14. Such a method of control is indicated by the lines 24 and 25.

The system of signaling heretofore mentioned which was invented by Wilmer W. Salmon and Frank L. Dodgson, provides means whereby trains moving in the same direction can enter the single track block without waiting for a preceding train in the single track block to pass out therefrom. Such a system facilitates the movements of trains and allows a much larger number of trains to pass over a single track line in the same length of time, for, a train moving in the direction of the arrow x upon the single track block may be immediately followed into said block by another train moving in the direction of the arrow x which latter train may also be immediately followed by another train moving in the direction of the arrow x and so on.

As the mere presence of a train upon the clearing sections, to-wit: the section of track between insulating joints 14 and 15, and 21 and 22 causes either the signal 5 or the signal 8 to move to the clear position and as the signals 5 and 8 are ordinarily and should be interlocked electrically so that only one signal may be clear at a time, it must be readily seen that a train moving in the direction of the arrow x , would first move upon the clearing section A, causing the signal 8 to exhibit an operated aspect and after passing over the single track block, would enter upon the clearing section B and would then, by its mere presence upon the clearing section B, cause the signal 5 to exhibit an operated aspect, but by the movement of the signal 5 to exhibit an operated aspect, the controlling circuit for an operated aspect of signal 8 is broken, therefore, a following train moving in the direction of the arrow x moving upon the clearing section A, would be unable to cause the signal 8 to assume an operated aspect until the preceding train had passed beyond the limits of the clearing section B. In some cases the clearing section B is directly opposite a station or stopping place and, consequently, is occupied for a considerable length of time by a train and as the train prevents the exhibition of an operated aspect by signal 8 during all the time that it is upon the clearing section B, it is desirable to provide a means whereby a train moving in the direction of the arrow x will not

cause the signal 5 to exhibit an operated aspect and thereby break the circuit of the signal 8 so as to prevent the signal 8 from exhibiting an operated aspect to a following train moving in the direction of the arrow x . 70

It is also objectionable from the standpoint of economy to allow signals 5 or 8 to clear behind a train, for such a clearing movement would be a needless waste of energy, and furthermore a clearing of either signal 5 or 8 under such conditions would cause a reversal of the positions of the intermediate signals as ordinarily controlled thus resulting in a further waste of energy. 80

As heretofore stated it is a primary object of applicant's invention to provide such a means as before stated, which means is shown diagrammatically by Fig. 2, in which:

A, designates the clearing section consisting of the portion of trackway included between the insulating joints 14 and 15, and C designates the section of trackway included between the insulating joints 15 and 16 as shown by Fig. 1. 85

In Fig. 2, 26 designates a source of current, the two terminals of which are connected to the two track rails 27 and 28; 29 designates a source of current the two terminals of which are connected to the two track rails 27 and 28; 30 and 31 designate electro-magnets, the terminals of which are connected to the track rails 27 and 28 in the sections A and C, respectively; 32 and 33 designate movable armatures controlled by the electro-magnet 30; and 34 and 35 designate movable armatures controlled by the electro-magnet 31; 36 designates a source of current; 37 designates an electro-magnet controlling movable armatures 38 and 39. 105

The movement of a train onto the section A, moving in the direction of the arrow x , causes a deenergization of electro-magnet 30, as the current from the source 26 is shunted through the wheels and axles of the train thus causing relay armatures 32 and 33 to drop upon back contact points. A circuit will be thus formed in which current flows as follows: positive terminal of current source 36, wires 40 and 41, armature 39, wire 42, armature 33, wire 44, armature 35, wire 45, signal mechanism at signal 8, wires 46 and 47 to the negative terminal of the source of current. The current flowing in the above traced path will cause the motor attached to the semaphore arm of signal 8 to move, thus moving the semaphore arm of signal 8 to an operated aspect 120 as is well understood by those skilled in the art. The movement of the train upon the section C thereafter, will cause the arm- 125

ture 35 to drop, thus breaking the continuity of the circuit above traced and thus causing the semaphore arm of signal 8 to return to the danger or horizontal position, thus protecting the rear of the train.

According to the object of applicant's invention as heretofore stated, if a train should approach the signal 8, moving in the direction of the arrow *y* and then pass upon the section A, no movement of the semaphore arm of signal 8 should take place. In order to accomplish such object, applicant has made use of the electro-magnet 37, which is energized when a train spans the insulating joints 15, part of the train resting upon the section C and part upon section A. Under such conditions current flows in the following path: positive terminal of the source of current 36, wires 40 and 48, armature 32, which is under such conditions in its lower position, wire 49, electro-magnet 37, wires 50 and 51, armature 34, which is under such conditions in its lower position, and wires 52 and 47 to the negative terminal of the source of current 36. The current flowing in the above traced path energizes the electro-magnet 37 and causes the armatures 38 and 39 to move upwardly so causing the continuity of the previously described signal circuit to be broken between armature 39 and wire 41.

In order, however, to fully attain the object of applicant's invention, the armature 39 must be held in its raised position during all of the time that the train which entered section A, moving in the direction of the arrow *y*, is upon the rails of clearing section A. Such a result is accomplished by causing a continued energization of the electro-magnet 37 by current flowing in the following path: positive terminal of the source of current 36, wires 40 and 48, armature 32, which is when a train is upon section A in its lower position, wire 49, electro-magnet 37, wires 50 and 53, armature 38 and wires 54 and 47 to the negative terminal of the source of current 36. The current in the above traced path flows as long as the train considered, is upon the rails of section A, consequently, the circuit for the signal 8 is maintained broken between wire 41 and armature 39, and although the normally open break between armature 33 and wire 42 is closed, no current can flow in the circuit to move the signal 8 to an operated aspect. It is, of course, to be understood that other means for controlling the circuit of the signal 8 will ordinarily be interposed in the wires 45 and 44.

Applicant has, therefore, devised a means whereby a signal governing the entrance of a track circuited block as C, may be moved to an operated aspect by the entrance of a train upon a track circuited clearing section

as A when the train enters upon such track 65 circuited clearing section at the end remote from the track circuited block, which means, also prevents a movement of the signal to an operated aspect if a train enters upon the track circuited clearing section after having 70 first moved over the track circuited block and the result is accomplished solely by means governed by the track circuited block and the track circuited clearing section.

In the system invented by Wilmer W. 75 Salmon and Frank L. Dodgson heretofore referred to, a normally open circuit is closed by the entrance of a train from one direction into a block section, and is not closed by the entrance of a train into the block 80 from the other direction. Such a circuit could be used to govern a signal in the manner shown in this application, by applying such system of control to signal 2 for instance and thereby controlling the clearing 85 of signal 8 by direction of train movement, for which reason, as this invention embodies a principle of operation, to-wit: the control of a circuit by the direction of train movement, it is considered to be a specific form 90 of the generic invention fully shown, described and claimed in the joint application of Wilmer W. Salmon and Frank L. Dodgson, heretofore mentioned.

Having thus described a preferred form 95 illustrating the principle of my invention, what I claim as new and desire to secure by Letters Patent, is:

1. In a block signal system; a trackway composed of rails; means to divide the 100 trackway into a forward track circuit section and a rear track circuit section; sources of current one connected to the rails of each section; translating devices, one connected to the rails of each section; a third translating 105 device; a signal; a normally open circuit including said signal; a normally open break in said circuit controlled by the translating device connected to the rear section; a normally closed break in said circuit controlled 110 by the forward section; a normally closed break in said circuit controlled by the third translating device; a normally open circuit for the third translating device; two normally open breaks in said last mentioned 115 open circuit controlled, one by the translating device connected to the rear section and one controlled by the translating device connected to the forward section; a second normally open circuit for the third translating 120 device including the normally open break last mentioned controlled by the translating device connected to the rear section; a normally open break in said last mentioned open circuit controlled by the third translating device itself; a source of current for supplying energy to said circuits.

2. In a signaling system for railways, in

combination; a stretch of track divided into two track circuit sections; a normally open circuit; means controlled by the track circuit of one of said track sections for closing 5 a normally open break in said circuit when that track section is occupied; means controlled by the track circuit of the other track section for opening a normally closed break in said circuit when said other track section 10 is occupied; a translating device; means governed by said translating device and rendered effective when said device is energized for preventing the closing of said circuit; controlling circuits for said translating device, one of said controlling circuits being governed jointly by the track circuits of both of said two track sections and being closed when both of said track sections are occupied, the other of said controlling circuits being governed separately by the track circuit of the first mentioned track section, and being closed when said first mentioned track section is occupied and said translating device is energized; and means for signaling governed by said normally open circuit. 15 20 25

3. In a signaling system for railways, in combination: a track circuit block; a signal for guarding the entrance to said block; and having a normal biased position and operated position; a track circuited clearing section in the rear of said signal; a circuit for governing said signal controlled jointly by the track circuit of said clearing section and a track circuit of said block and being capable of being closed when said clearing section is occupied and said block is not occupied; a normally closed circuit controller included in said circuit; means for operating said circuit controller; a preliminary energizing circuit for said last mentioned means governed jointly by the track circuit of said clearing section and a track circuit of said block; and a maintaining circuit for said last mentioned means governed separately by the track circuit of said clearing section.

4. In a signalling system for railways, in combination: a stretch of track divided into track circuit sections; a signal for governing traffic in one direction of said stretch; a circuit for controlling said signal; a stick relay for governing said circuit; and two controlling circuits for said stick relay, one of said controlling circuits being governed 50 jointly by the track circuits of a track section in advance of and a track section in the rear of said signal, and the other of said controlling circuits being governed separately by the track circuit of the track section 55 in the rear of said signal.

5. In a signaling system for railways, in combination: a stretch of track divided into track circuit sections; a signal for governing traffic in one direction of said stretch;

a circuit for governing said signal controlled 65 by the track circuit of a track section in advance of said signal and interrupted when that track section is occupied; a normally closed circuit controller included in said circuit; a stick relay for governing said circuit 70 controller; a normally open preliminary energizing circuit including said stick relay and governed jointly by the track circuits of two of said track sections adjacent to the signal; and a normally open maintaining 75 circuit including said stick relay and governed separately by the track circuit of one of said two track sections and by said relay itself.

6. In a signaling system for railways, in combination: a stretch of track divided into track circuit sections; a signal for governing traffic in one direction of said stretch; a circuit for controlling said signal governed by a track circuit of a track section in the rear of said signal; and means including a normally deenergized stick relay for nullifying the controlling effect produced on said circuit by the track circuit of said rear track section when a train moving in the direction opposite to the direction of traffic governed by said signal passes into said rear track section. 85 90

7. In a signalling system for railways, in combination: a stretch of track divided into 95 track circuit sections; a signal for governing traffic in one direction of the stretch; a circuit for controlling said signal; a normally deenergized stick relay for controlling said circuit; a preliminary energizing circuit 100 for said stick relay governed jointly by track circuit sections on opposite sides of the signal; and a maintaining circuit for said stick relay controlled by a track circuit section in the rear of the signal independently of any 105 track circuit sections in advance of the signal.

8. In a signaling system for railways, in combination: a stretch of track divided into track circuit sections; a signal for governing traffic in one direction; a normally closed circuit controller; a normally deenergized stick relay for opening said circuit controller when energized; a preliminary energizing circuit for said stick relay controlled jointly by track circuit sections on opposite sides of the signal; a maintaining circuit for said stick relay including a front contact thereof and controlled by a track circuit section on one side of the signal independently of any track circuit section on the opposite side of the signal; and a circuit for signaling including said circuit controller. 110 115 120

9. In a signaling system for railways, in combination: a stretch of track; a signal for governing traffic in one direction; a circuit 125 for controlling said signal; a normally closed circuit controller included in said circuit; and means including a normally deenergized

stick relay for opening said circuit controller and maintaining it open when a train travels in the direction opposite to the direction of traffic governed by the signal and until such train has advanced to a predetermined point in the rear of the signal.

10. In a signaling system for railways, in combination: a stretch of railroad track; a signal for governing traffic in one direction; a normally closed circuit controller; a normally deenergized stick relay for opening said circuit controller when energized; circuit controlling devices separately responsive to the presence of any part of the train 15 on predetermined portions of the track on opposite sides of the signal; a preliminary energizing circuit for said stick relay including said circuit controlling devices; a maintaining circuit for said stick relay including 20 a front contact thereof and having its continuity otherwise dependent solely upon the

presence of a train on a predetermined portion of the track extending from one side of the signal; and a circuit for signaling including said normally closed circuit controller. 25

11. In a signaling system for railways, in combination: a stretch of track; a signal for governing traffic in one direction; a circuit for controlling said signal; a normally deenergized stick relay for interrupting said circuit when energized; means for energizing said stick relay by trains traveling in either direction; and means for maintaining said stick relay energized after it has been initially energized so long as a train occupies a predetermined portion of the track in the rear of said signal. 30 35
